RAZOR BLADE HOLDER

Filed May 7, 1931

UNITED STATES PATENT OFFICE

CARL GORNEMAN, OF CAMDEN, NEW JERSEY

RAZOR BLADE HOLDER

Application filed May 7, 1931. Serial No. 535,741.

This invention relates to razor blade holders designed to provide a handle for an ordinary safety razor blade and particularly to razor blade holders of that type in which two shank sections are adapted when closed to engage the razor blade and clamp it in position.

One of the objects of the present invention is to provide a very simple and easily operated blade holder which may be cheaply made and cheaply sold.

A further object is to provide a razor blade holder having two closable shank portions constituting jaws, means normally urging said shank portions and jaws to an open position, and means for holding the jaws in clamped engagement with a razor blade, the construction being such as to permit free movement of the shanks with relation to each other.

My invention is illustrated in the accompanying drawings, wherein:—

Figure 1 is a top plan view of a razor blade holder constructed in accordance with my invention;

Figure 2 is an elevation of the same closed;

Figure 3 is an elevation showing the shanks of the blade holder open;

Figure 4 is a longitudinal fragmentary section of the rear end of the blade holder with the shanks closed;

Figure 5 is a like view to Figure 4 but showing the shanks open;

Figures 6 and 7 are sections respectively on the lines 6—6 and 7—7 of Figure 1.

Referring to these drawings, it will be seen that my razor blade holder comprises two semi-tubular shank portions 10 and 11, the shank 11 being slightly less in diameter than the diameter of the shank 10. These shanks 10 and 11 at their forward ends are provided with the laterally extending flanges 12 and 13 adapted to confront each other. The flanges 12 are relatively wide and one of these flanges, as shown in Figure 6, is formed with apertures 14 while the other flange is formed with depressed bosses 15 engageable with these apertures, these bosses being adapted to project through the perforations in a certain style of safety razor blade to hold

the blade in place. Where another style of razor blade is to be held, this style having a "back", the back is placed between the two semi-circular shanks and the blade passed between the flanges 13.

It will be seen that the parts 12 and 13 constitute jaws which are formed as part of the shanks 10 and 11. The shanks are joined at their rear ends by means which will now be described. As shown in Figures 4 and 5, there is disposed between the rear ends of the shanks a double spring designated generally 16. This spring is formed to provide an annular bight 17 from which two spring jaws 18 and 19 extend, these jaws being curved away from each other. The rear ends of the shanks 10 and 11 are formed with slots 20 adapted to receive opposite portions of the annulus 17 while the extremities or leaves of the spring bear against the shanks and urge the shanks apart, the annulus 17 constituting a portion upon which the shanks may relatively rock.

As shown in Figure 5, the shank 11 is formed at its rear end with a downwardly curved end portion 21 and the shank 10 with an upwardly curved end portion 22. This extends upward beyond and slightly overlaps the end portion 21. In order to hold the two shanks in engagement with the spring annulus 17, I provide a cap 23 which is of such diameter that it slips over the joined ends of the shanks and holds these shanks upon the circular portion of the spring but permits the shanks to have free movement relative to each other. Of course the shank 10 is practically rigid with the cap 23 and the shank 11 is movable relative to the shank 10 and relative to the cap, as clearly shown in Figure 5.

For the purpose of holding the shanks closed upon each other, I provide the shank 10 with a slide 24 shown most clearly in Figure 7, this slide having inwardly turned end portions 26 which engage over flanges 25 formed upon the lateral margins of the shanks 10 and 11 adjacent the blade holding jaws of these shanks, one of the flanges 24 being shorter than the other flange to permit disengagement of the slide 24 from shank 11,

thus allowing the shanks to spread apart under the action of the spring.

Thus it will be seen that when the shanks are closed against each other to engage a 5 blade, the slide 24 may be shifted to hold the shanks closed, as shown in Figure 2, but when the slide is retracted, the shanks and the jaws carried thereby will open.

It will be seen that I have provided a blade 10 holder which is very readily manipulated by holding the shanks in one hand and using the finger or thumb of that hand to shift the slide 24 either to its release position to open the shanks or to its closed position to close the 15 shanks. It thus requires only one hand to manipulate the holder, the other hand being used to insert the blade, after which the jaws are closed. It will also be seen that I have provided a very simple and effective device 20 for this purpose which may be cheaply manufactured, as it consists of but few parts and these are of very simple character.

The spring 16 acts not only as a spring urging the shanks and jaws apart, but as a means 25 for operatively connecting the jaws to each other, preventing longitudinal movement of the jaws with relation to each other and permitting the rocking movement of the jaw 11 with reference to the jaw 10. It will be understood that the cap 23 is forced firmly upon 30 these jaws and that there is sufficient friction after the cap is forced in place so that the cap cannot be removed except by extreme force. This friction is due to the fact, as shown in 35 Figures 4 and 5 that the cap engages the spring annulus 17. The razor blade so held may be used for a large number of different purposes and attention is called to the fact that when a razor blade is held between the 40 jaws with the jaws closed, the razor blade will project laterally beyond the central longitudinal axis of the holder and, therefore, the edge of the razor blade will tip downward toward a table or other object upon which the 45 holder is laid whereas in all constructions known to me, the razor blade is likely to be tipped up or held in spaced relation to the surface of the table when the implement is laid down thereon, thus holding the blade in 50 a very dangerous position where it is likely to cut somebody.

I claim:—

1. A razor blade holder of the character 55 described, comprising opposed shanks, each semi-circular in cross section, the rear ends of the shanks being formed with longitudinally extending slots, the opposite ends of the shanks being formed with confronting blade engaging jaws, a spring disposed between the shanks, the spring having an annular portion engaging at opposite sides in 60 said slots, and constituting a fulcrum upon which one of said shanks may rock, the material of the spring being extended from the 65 annulus to form two outwardly curved legs

engaging the opposite shanks and urging them apart, a cap extending over the rear ends of the shanks and engaging the annulus, the cap being of sufficient diameter to permit a limited movement of the shanks away from each other under the action of the spring, and means on one shank engageable with the other shank to hold the shanks closed against each other.

2. A razor blade holder of the character 70 described, comprising opposed shanks, each semi-circular in cross section, the rear ends of the shanks being formed with longitudinally extending slots, the opposite ends of the shanks being formed with confronting blade 75 engaging jaws, a spring disposed between the shanks, the spring having an annular portion engaging at opposite sides in said slots, and constituting a fulcrum upon which one of said shanks may rock, the material of the spring being extended from the annulus to form two outwardly curved legs engaging the opposite shanks and urging them apart, a cap extending over the rear ends of the shanks and engaging the annulus, the cap being of sufficient diameter to permit a limited 80 movement of the shanks away from each other under the action of the spring, the rear ends of the shanks being curved inward, one of the shanks extending rearward of the other and having its inwardly curved rear end extended rearward of the inwardly curved end of the other shank to permit the movement of this last named shank into angular relation to the first named shank.

3. A razor blade holder of the character 85 described including opposed shanks, each semi-circular in cross section, the rear ends of the shanks being formed with longitudinally extending slots, the opposite ends of the shanks being formed with confronting blade 90 engaging jaws, a spring disposed between the shanks, the spring having an annular portion engaging at diametrically opposite sides in said slots and constituting a fulcrum upon which said shanks may rock, the material of the spring being extended from the annulus to form two legs engaging the opposite shanks and urging them apart, and means for holding 95 the rear ends of the shanks in engagement with the annulus, said means permitting relative oscillation of the shanks toward and away from each other.

4. A razor blade holder having separate 100 shanks extending approximately parallel to each other, each shank terminating at one end in a jaw, the shanks being approximately U-shaped in cross section and disposed with their open sides confronting each other, one shank being less in diameter than the other shank to thus fit within the other shank, and means hingedly connecting the shanks to each other at a point forward of the rear ends of the shanks, said rear ends thus limiting the opening movement of the shanks, a dou- 105

ble ended spring disposed between the shanks and urging them to an open position, laterally projecting opposed lugs on the two shanks, and a slide movable longitudinally on the shanks extending under one shank and having its ends adapted to engage over the lugs of the opposed shank to provide means for clamping the shanks in parallel relation with the jaws closed.

10 In testimony whereof I hereunto affix my signature.

CARL GORNEMAN.
